OINTMENT APPLICATOR

Mack M. Werner, Brooklyn, N. Y.

Application June 26, 1947, Serial No. 757,257

12 Claims. (Cl. 128—261)

1

The invention relates to antiseptic dispensing means for ointment and similar medicaments.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a top plan of a protector sheath embodying the invention;

Fig. 2 is a view similar to Fig. 1, showing an ointment tube in place;

Fig. 3 is a side elevation of an ointment tube;

Fig. 4 is an enlarged fragmentary section on line 4—4 of Fig. 2;

Fig. 5 is a side elevation of Fig. 1; and

Fig. 6 is a section on line 6—6 of Fig. 5.

Ointments and other medicaments are usually conveniently furnished in small compressible tubes having screw caps, the ointment or other medicated contents being extruded from a suitable orifice at the end of the tube onto the affected part, such as the eye or nose. A common illustration of this is the application of ointment to the eye, wherein the desired quantity of material, such as mercuric oxide, for example, is extruded from the small opening at the end of the tube directly onto the eyelid or other affected portion of the patient's eye. It has been found that this method of application is a serious and frequent source of transferring infections because the feed end or nozzle of the tube, coming in contact with the eyelid or even the eyelashes, is readily infected and such infection is then passed on to succeeding persons to whom application of the same ointment tube may be made. However, short of the expensive expedient of discarding the tube after a single application, there has been no effective and convenient means for disinfecting the applicator portion of the tube between applications to patients.

This problem is made difficult because of the impracticability of immersing most ointment or other medicament tubes in boiling water for purposes of sterilization. Mercuric oxide ointment, for example, has a very low melting point and would be entirely liquefied and the contents lost by immersion in boiling water. Other common means of sterilizing are likewise impracticable, such, for example, as dipping the applicator end

2

of the tube in alcohol or other sterilizing fluid because such sterilizing fluid remaining on the applicator would seriously irritate or otherwise harm the delicate tissues of the eye. When it is understood that an ophthalmologist may employ up to 25 or 30 different medicament tubes in his practice, it will be clear that the problem is a substantial one.

The primary object of my invention is to provide means whereby ointment applicator tubes and similar medicament containers may be used repeatedly on successive patients without the slightest danger of picking up or transferring bacteria or other causes of infection from one patient to another. In accomplishing this object, the invention provides a simple, inexpensive, durable and convenient holder and protector for ointment in which the tube can be readily temporarily encased. Said protector or sheath is designed to hold the tube while in use for the application of ointment, guarding same from contact with the affected parts of the patient while the ointment is applied and also guarding against contamination of the exposed ointment in the tube nozzle or the applicator nozzle of the tube itself through handling by the doctor or nurses.

In accordance with the invention the tube protector or sheath is readily detachable from the ointment tube after use and is designed for rapid and thorough sterilization by boiling, steaming or other equivalent sterilizing operation. The protector of the invention is designed so as to be interchangeable with others so that it can be applied readily and used with any tube of standard design. Another object of the invention is to provide, during encasement and use of the tube, a convenient and sterile means for guarding and saving the screw cap of the ointment tube so that it will remain with its own tube and not become mixed with others or handled in such a way as to become contaminated or to transfer infection to the tube or its ointment.

It will be understood that the foregoing general description and the following detailed description as well are exemplary and explanatory but are not restrictive of the invention.

Referring now in detail to the present preferred embodiment of the invention shown by illustration in the accompanying drawings, the sterilizing sheath or protector generally indicated by 1 is designed to fit about and replaceably contain a conventional ointment tube T. Said tubes are customarily made of tin or other compressible material, having a tapered elongated applicator end and nozzle 2 through which the ointment may be extruded and applied in small quantities to the affected parts of the patient. Said applicator nozzle is normally threaded to

receive an internally threaded screw cap closure 3. The opposite or base end of the compressible tube is usually closed by a flattened crimped seal 4. It will be understood that the foregoing description of said tube is intended to be generic to a common form of ointment container usually made in sizes from $\frac{1}{8}$ to $\frac{1}{2}$ oz. capacity and used in great quantities by physicians in the treatment of the eyes and similar forms of therapy. It is the applicator nozzle 2 of such tubes which normally comes in contact with the patient and which is contaminated thereby.

In accordance with the invention I provide the protector sheath 1 for housing and permitting use of said tubes T in a sterile manner. Said sheath as formed comprises a main cylindrical barrel or body 5 which is internally shaped and sized to readily receive and house a tube T. The forward or nose portion 6 of sheath 1 is completely circular in cross-section and tapers forwardly to a hollow tubular nose or nipple 7. Said forward end portion of the sheath is designed to receive and house the forward portion 2 of the tube T as shown so that when ointment is extruded from said tube it passes from the end portion 2 thereof through the tubular nipple 7 of the sheath and thus may be applied to the affected parts of the patient in essentially the same manner as by use of the tube itself.

The cylindrical barrel 5 of the sheath is cut away to the rear of the head portion 6 to leave the upper part of said barrel open, the side walls being inclined downwardly and rearwardly at 8 as shown. This permits ready access to the intermediate portion of the tube for squeezing and ointment extrusion. The rear portion of the barrel terminates in a rearwardly extending tail 10 which is a prolongation of the bottom element of the cylindrical body 5. To form said narrow tail portion 10, the rear parts of the side walls of the barrel 5 are tapered rather sharply at 11. Inclined side walls 8 may be flared outwardly at a central portion of their length as at 12 so that when pressure of the thumb or finger is applied to the tube T the edges of the side walls do not cut or indent the flesh upon repeated use.

For the purpose of most conveniently engaging and holding the tube T in position within the protecting sheath, the rear portion of the sheath is provided with a movable or adjustable retainer or clamp member by means of which the physician or attendant may conveniently engage and temporarily fasten the tube T in place after same has been laid in position within the sheath. For this purpose a clamping member 14 is provided comprising a conical tip 15, reduced shank 16 and threaded portions 17 and 18. Threads 17 engage an internally threaded barrel 19 which is formed at the outer end of tail portion 10. When the tube T is in place in the sheath, the crimped seal 4 thereon may be gripped and clamped in place by turning the member 14 in the proper direction until the conical tip 15 engages and wedges the seal 4 against tail 10.

To prevent the clamping member 14 from being inadvertently unscrewed from the tail barrel 19 and thus lost, a tab 20 may be stamped out of tail 10 adjacent the inner end of tail barrel 19 and, after assembly of clamp member 14 in the barrel 19, bent upwardly to engage lightly the shank portion 16 and lie in the path of the rear shoulder of the conical tip 15 as the latter may be retracted by unscrewing.

For facilitating the holding of the assembled

article, the bottom portion of the protector sheath barrel 5 may be provided with knurling 25 to provide a convenient grip and avoid the danger of the user's hand slipping forward to contaminate the nipple portion 7 while the tube is being set in the sheath. It will be noted that the tail piece 10 and the parts mounted thereon are preferably bent upwardly rearwardly at a slight angle to facilitate holding the tube in place.

10. In accordance with the invention it is also desirable to assure that the screw cap 3 of tube T is not misplaced, contaminated, or mixed with similar caps of other tubes, especially those containing different ointments. This confusion may 15 readily occur because the physician uses a considerable number of such tubes giving treatments and the caps are normally all the same size, shape and color. Accordingly I provide a convenient threaded portion 18 formed at the rear end of the clamping member 14 upon which the threaded cap may be temporarily screwed during the time that the tube T is housed within the sheath and, at the same time, act as a finger grip for turning member 14. This assures that the user will 20 always have the cap 3 in his hand when it is detached either from the tube or the member 18.

In use, a tube T is inserted into a sterilized sheath 1 as shown in Fig. 4, the cap of said tube being first removed and screwed onto the threaded member 18. The tube is readily available for compression to squeeze ointment out of its end, while the sterile nipple 7 acts to prevent infection in use. After the physician has applied the ointment to the patient by use of the sheath as shown, the assembled sheath and tube are then put by him into a non-sterile tray. The nurse then takes it and other similar assemblies, removes the tubes therefrom and screws on their respective caps without touching or contaminating the exposed applicator ends 2 of said tubes. The sheaths 1 are placed in a boiling water sterilizer and a whole batch thereof may be sterilized at one time and they are then ready for reuse with any desired tube.

45. The material of which the sheath is made is preferably stainless steel, although it may be any suitable material which is sufficiently strong and rigid for the work intended and which can be sterilized by boiling in water or equivalent high temperatures.

The invention in its broader aspects is not limited to the specific mechanisms shown and described, but departures may be made therefrom within the scope of the accompanying claims without departing from the principles of the invention and without sacrificing its chief advantages.

What I claim is:

60. 1. A sterilizable protector for ointment tubes and the like including in combination a tube-supporting container in which an ointment tube may be removably housed, said container having a sheath for enclosing the dispensing end of said tube, and an opening in said sheath for delivery of ointment extruded from the tube, said container having means at the end opposite said dispensing end for holding said tube in said container.

65. 2. A sterilizable protector for ointment tubes and the like including in combination a removable housing for an ointment tube, said housing having a covering for the dispensing end of the tube, said covering including a sheath enclosing the nozzle at the tube end and guarding same from contact

75

with surfaces to which ointment is applied, and a conduit through said sheath for delivery and application of ointment extruded from the tube, said removable housing including clamping means at the opposite end from said nozzle end for temporarily locking said tube in said housing.

3. A sterilizable protector for ointment tubes and the like including in combination a removable housing for an ointment tube, said housing having an end shaped to receive and enclose the dispensing nozzle of the tube, said end including a dispensing nipple for delivering and applying ointment from the tube and for guarding the tube nozzle from external contact, said removable housing including adjustable clamping means at the opposite end from said dispensing end for removably retaining said tube in said housing.

4. A protector as specified in claim 3 wherein said housing is partially open to expose the tube for compression.

5. A sterilizable protector for ointment tubes and the like including in combination a removable housing for an ointment tube, said housing having an end shaped to receive and enclose the dispensing nozzle of the tube, said end including a dispensing nipple for delivering and applying ointment from the tube and for guarding the tube nozzle from external contact, said housing comprising a cylindrical body adapted to receive and support said ointment tube therewithin, a portion of said body being cut away to expose the tube for compression between its ends, the end of the housing receiving the nozzle of the tube being round in cross-section and tapering forwardly to provide said nipple and having a tubular bore extending therethrough and communicating with the nozzle of the tube when the tube is seated therewithin, and a movable clamp at the opposite end of the housing for engaging and holding the bottom end of said tube.

6. A sterilizable protector for ointment tubes and the like including in combination a sheath for enclosing the nozzle of an ointment tube having an outlet for delivery of ointment extruded from the tube and movable gripping means at the end opposite said delivery outlet for temporarily attaching said sheath to the tube.

7. A sterilizable protector for tubes, such as ointment tubes or the like, having a removable cap, said protector including in combination a removable housing for said tube, said housing having an end shaped to receive and enclose the dispensing nozzle for delivering and applying ointment from the tube and for guarding the tube nozzle from external contact, said removable housing including adjustable clamping means at the opposite end from said dispensing end for removably retaining said tube in said housing, and means for retaining said tube cap when it is detached from the tube.

8. A sterilizable protector for ointment tubes and the like including in combination a sheath for enclosing the nozzle of an ointment tube and having an outlet for delivery of ointment extruded from the tube, and adjustable clamping means at the end opposite said dispensing outlet for temporarily attaching said sheath to said tube, said clamping means comprising a tail portion extending from the body of said protector and a threaded bolt attached to said tail portion for engaging the rear end of said tube.

9. A sterilizable protector for ointment tubes and the like including in combination a sheath for enclosing the nozzle of an ointment tube and

having an outlet for delivery of ointment extruded from the tube, and adjustable clamping means at the end opposite said dispensing outlet for temporarily attaching said sheath to said tube, said 5 clamping means comprising a tail portion extending rearwardly from the central portion of said protector at an angle inclined with respect to said central portion, a hollow barrel portion at the rear end of said tail portion, and a threaded bolt adjustably positioned in said barrel so as to contact the end of said tube opposite the dispensing end.

10. A sterilizable protector for ointment tubes and the like including in combination a tube-15 supporting container in which an ointment tube may be removably housed, said container having a sheath for enclosing the dispensing end of said tube, an opening in said sheath for delivery of ointment extruded from the tube, and movable 20 gripping means for removably pinioning said tube in said housing, said means comprising a portion extending from the rear end of said housing in an upwardly and rearwardly direction with respect to the central body portion of said 25 housing, a cylindrical retaining member at the back end of said rear portion, and a threaded stud engaging the walls of said retaining member and adjustably mounted in said member, said stud having a head facing the rear end of said tube.

11. A sterilizable protector for ointment tubes and the like including in combination a removable housing for an ointment tube, said housing having a covering for the dispensing end of the 35 tube, said covering including a sheath enclosing the nozzle at the tube end and guarding same from contact with surfaces to which ointment is applied, a conduit through said sheath for delivery and application of ointment extruded from 40 the tube, and clamping means for removably pinning said tube in said housing, said means comprising a tail portion extending rearwardly from the bottom of said body portion of said housing in a direction in acuity with said body 45 portion and a tab raised from said tail portion and in engagement with the shank of said stud.

12. A sterilizable protector for tubes, such as ointment tubes or the like, having a removable cap, said protector including in combination a removable housing for an ointment tube, said housing having an end shaped to receive and enclose the dispensing nozzle of the tube, said end including a dispensing nozzle for delivering and applying ointment from the tube and for 55 guarding the tube nozzle from external contact, said removable housing comprising a portion extending from the rear end of said housing in an upwardly and rearwardly direction with respect to the central body portion of said housing and a stud having a shank portion adjustably mounted in said tail portion for engaging the rear end of said tube, said stud also having a further shank portion of diameter approximately that of said tube cap for temporarily retaining 60 said tube cap when it is detached from said tube.
